BEACH ACCESSORY

Nelson M. Jones, Sarasota, Fla.

Application November 7, 1935, Serial No. 48,739

4 Claims. (Cl. 135—5)

This invention relates to a beach accessory. It is particularly aimed to provide a novel means which is convertible to or from a handbag to or from a headrest with suitable sunshade.

5 The more specific objects and advantages will become apparent from a consideration of the description following taken in connection with accompanying drawing illustrating an operative embodiment.

10 In said drawing:—

Figure 1 is a view in perspective showing the invention used as a headrest;

Figure 2 is a view of the invention in perspective showing its use as a handbag;

15 Figure 3 is a substantially central longitudinal sectional view taken through the invention in the condition of Figure 1;

Figure 4 is a detail cross sectional view taken on the line 4—4 of Figure 3; and

20 Figure 5 is a detail cross sectional view taken on the line 5—5 of Figure 3.

Referring specifically to the drawing, the invention involves three panels or walls, A, B, and C. Panel A is designed to function as a head-

25 rest or pillow in some instances and it consists of a textile fabric casing 10 containing an upholstered filling 11 and also containing reinforcing metallic or wire frame 12 having arcuate free ends 13 extending exteriorly of the casing 10.

30 Said panel B consists of an endless metallic or wire frame 14, preferably covered with canvas or other textile fabric 15. Said free ends 13 are pivotally connected at 16 to the frame 14, and in the vertical position of panel B, it abuts a stop member 17 forming part of the frame 12 of pillow A.

35 Reverting to the panel C, it consists of a metallic or wire frame 18, covered with canvas or other textile fabric 19, which, if desired, may be ornamental as shown, and colored after the fashion of awnings and canopies. Said frame 18 has arcuate free ends 20 beyond the fabric 19 which are pivoted at 21 to the frame 14, and the frame 40 has an abutment member 22 adapted to engage the frame 14 in the open position of the device, as shown in Figure 3.

45 Along opposite longitudinal edges of the casing 10, substantially triangular or other shaped flaps 23 are fastened and same through the medium of conventional separable fasteners 24 are adapted for detachable connection with one side of the canopy B, one part of each separable fastener 50 24 being fastened to the fabric 15, and the co-

acting part being fastened to the adjacent flap 23.

On the side of the panel B opposite to the separable fastener parts 24, a movable pocket 5 may be provided in which cigarettes or other small articles may be carried.

Handles of any suitable design are provided at 26 at one end of the panels A and B.

The device may be used in the bag form shown in Figure 2, or it may be used as a headrest, as 10 shown in the form of Figures 1 and 3. In such form as Figures 1 and 3, the head is adapted to rest on the panel A as a pillow, and the weight of the panel C is adapted to maintain the frame B in contact with the abutment 17 and the panel 15 C at the abutment 22 in contact with the frame 14.

In the folding of the device from the form of Figures 1 and 3 into the bag form of Figure 2, panel C is swung to the right in Figures 1 and 3 into parallelism with panel B, and such panel as 20 a unit thereafter swung into parallelism with the panel A, whereupon the separable fasteners 24 are connected.

When the panel A functions as a pillow, it is 25 adapted to rest upon the sand along the beach, thus being horizontal. The panel C under such circumstances serves as a cover or canopy, and the panel 14 also serves to cut off undesirable direct rays of the sun.

Attention is also called to the fact that the 30 hinge or pivotal joints at 16 and 21 may be sufficiently frictioned tight to hold the part in the different adjusted positions against danger of accidental displacement.

Various changes may be resorted to provided 35 they fall within the spirit and scope of the invention.

I claim as my invention:—

1. A device of the class described having parallel panels, a connecting panel pivoted to each of the first-mentioned panels, an abutment means on each of the parallel panels engageable by the connecting panel and maintained in such engagement through the weight of the uppermost parallel panel. 45

2. A device of the class described having parallel panels, a connecting panel pivoted to each of the first-mentioned panels, an abutment means on each of the parallel panels engageable by the connecting panel and maintained in such engagement through the weight of the uppermost parallel panel, said parallel panels having arcuate portions between their pivot elements and the zones of abutment. 50

3. A device of the class described having par- 55

- parallel panels, a connecting panel pivoted to each of the first-mentioned panels, an abutment means on each of the parallel panels engageable by the connecting panel and maintained in such engagement through the weight of the uppermost parallel panel, one of the parallel panels being foldable against the connecting panel, the last two panels being foldable as a unit into bag form with the remaining first-mentioned panel, and flaps to connect the latter panel and the connecting panel separably together.
4. A device of the class described having an upholstered panel adapted to serve as a pillow, a frame within said panel having arcuate por-

tions and an abutment exteriorly of the panel, a panel foldable relatively thereto having a frame to which said portions are pivoted, said frame being adapted to engage said abutment and assume a position at substantially a right angle to the pillow, a cover panel having a frame, said frame having an abutment and arcuate portions extending therefrom, said arcuate portions being pivoted to the second-mentioned frame and the latter being adapted to engage the second-mentioned abutment, flaps on the pillow, means of separable connection between the flaps and the second-mentioned panel.

NELSON M. JONES.
